UNITED STATES PATENT OFFICE.

ROBERT FRANCIS STEWART, OF SIOUX LOOKOUT, ONTARIO, CANADA.

SIGNAL.

1,371,127.

Specification of Letters Patent.

Patented Mar. 8, 1921.

Application filed September 15, 1919. Serial No. 324,005.

To all whom it may concern:

Be it known that I, ROBERT F. STEWART, a citizen of Canada, residing at Sioux Lookout, in the Province of Ontario and 5 Dominion of Canada, have invented new and useful Improvements in Signals, of which the following is a specification.

The present invention has reference to a signaling device for locomotives.

10 The improvement is in the nature of a classification signal as the same displays a white flag for day or a white light for night to denote an extra train, while a green flag for day and a green light for night is displayed to denote a section of a regular train or how one train is running on the time of 15 a regular train.

The object of the invention is to produce a signaling device of this character which 20 shall be of an extremely simple construction and which may be operated from the cab of the engine.

Other objects and advantages will present 25 themselves as the nature of the invention is better understood, reference being had to the accompanying drawings in which there is illustrated a simple and satisfactory embodiment of the improvement reduced to practice, it being understood, however, that 30 the nature of the invention is such as to render the same susceptible to various modifications, all of which falling within the scope of what is claimed.

In the drawings:—

35 Figure 1 is a side elevation of a locomotive provided with the improvement, parts being broken away.

Fig. 2 is an elevation of the improvement on an enlarged scale.

40 Fig. 3 is an end elevation with the lamps removed.

Fig. 4 is a top plan view of the improvement.

Fig. 5 is a longitudinal sectional view approximately on the line 5—5 of Fig. 4.

Fig. 6 is a detail sectional view through the front of the locomotive cab, illustrating the arrangement of the operating levers and the method of locking the same to hold one 50 of the signals in signaling position.

Fig. 7 is a diagrammatic view of the electric wiring.

To the side of a locomotive 10 there is secured the casing 11 of my improved classification signal. Preferably the casing 11 is bolted or otherwise connected to the hand

rail 12 as well as to the boiler of the locomotive.

The casing 11 is preferably constructed of two parallel rectangular plates, connected 60 together by suitable bolts 13 having their threaded ends engaged by nuts 14 and the body portion of the bolts between the plates constituting the casing are received in tubular sleeves 15. The sleeves contacting with the 65 inner faces of the plates hold the same properly spaced, and locking means of any desired construction may be employed for holding the nuts on the bolts. Passing through the plates adjacent to the upper and outer 70 corner of the casing is a pivot member preferably in the nature of a bolt 16 which has its threaded ends engaged by nuts 17 which are locked to the bolts in any desired or preferred manner. The pivot member 16 75 may, if desired, have its portion received between the plates of the housing surrounded by a sleeve, and the said member 16 provides an axle for bearing members 18 formed adjacent to the inner ends of the signal arms. 80 Each of the signal arms is similarly constructed, but for distinction the same are designated by the numerals 19 and 20 respectively. The arms 19 and 20 are formed from a single strip of suitable material, 85 metal preferred, and are, adjacent their inner ends given a half twist upon themselves so that the flattened portions thereof, indicated by the numerals 21 are at all times received in the casing 11. These flat portions are provided with the bearings 18, while the straight portions 22 of the said arms have secured thereto signal plates 23 and 24 respectively. The plate 23 is colored green while the plate 24 is white. 90 The portions 21 of the signal arms, adjacent to the ends thereof are formed with slots 25 and through these slots pass rods 26 and 27 respectively, the inner ends of the said rods being headed as at 28, and the inner edges of 100 the said heads are preferably beveled at the corners thereof to provide the inner and active faces of the heads with pointed portions 29. The heads are of a length approximately equaling the length of the slots 25 105 so that by turning the rods to bring the heads in alignment with the slots the said heads may be passed through the slots, and thus removed from the signal arms. In operative position, the heads are arranged transversely 110 of the slots. The rods 27 are guided through suitable bearings 30 in the rear of the casing,

and the said rods have their ends which project through the rear of the casing coupled to additional rods, the last mentioned rod sections having their ends headed, as at 31, 5 and the said rods pass through suitable openings 32 in the front wall 33 of the engine cab 34. Each of the heads 31 is provided with an opening 35 that serves as a finger hold for the operator, and in addition to this, each of 10 the rods, at a suitable distance away from its head is provided with a transverse opening 36. The head of the rod which operates the white signal has the word "White" imprinted thereon and the other rod which 15 operates the green signal has the word "Green" imprinted on the head thereof. When either of the signals is to be operated the operating rod therefor is pulled inward of the cab until the opening 36 is brought 20 to a line with the inner face of the cab wall 33. Suspended from the said inner face of the cab wall by means of a flexible element such as a chain 37 is a pin 38, and this pin is inserted through the opening 36, and in 25 this manner the signal is held in operative position. It will be apparent that a release of the rod will permit of the signal to drop by gravity into the casing.

In addition to the signals above described, it is necessary that illuminative signals be provided in order that proper signaling can take place at night, and to accomplish this I attach at the front of the casing 12 in any desired or preferred manner a lamp box 39. This box is divided into an upper and a lower compartment, the upper compartment having an outer transparent casing which is green in color and which is designated by the numeral 40. The 30 casing 40 is designed to transmit the rays from the electric lamp bulb 41 therein through both the front and outer side of the said casing. The lower compartment has a transparent casing 42 which is white, 35 so that white rays from the lamp bulb 43 will pass therethrough. The lamp bulbs 41 and 43 are in circuit with wires connected with the head light circuit, as illustrated in Fig. 7 of the drawings and are also connected to a switch comprising contact members 44 and 45 that are arranged in a suitable box 46 secured at the front end and at the top of the casing 12. The contact member 45 may be slidable, being spring 40 influenced in an outward direction of the box 46, and the slidable contact members 45 are in the path of engagement with the respective signal arms, and in this manner when either of the signal arms are 45 brought to signaling position one of the lamps will be illuminated. If desired, one of the contacts for the switch may be carried by the signal arms.

It is believed, from the foregoing description, when taken in connection with the drawings, the simplicity of the construction and the advantages thereof will be readily apparent without further detailed description.

Having thus described the invention, what is claimed as new, is:—

1. In a classification signal for locomotives, a casing having open ends, top and bottom secured to one side of the locomotive, two spaced arms having angle ends 75 pivotally secured in the casing, a signal secured to the outer portion of each of the arms of sufficient weight to normally swing the arms and retain the signal in the casing, slidably operating rods for the offset end of each of the arms passing through openings in the cab of the locomotive, said arms having their ends headed, the said heads provided with finger openings and the said rods a distance from the heads 85 thereof each having a transverse opening, said heads designed to abut with the wall of the cab when the signals are in non-signaling position and are arranged in the casing, and a flexibly supported pin 90 designed to pass through the opening in either of the rods and to contact with the wall of the cab for holding either of the signals in signaling position, after the rod has been pulled longitudinally to bring the said 95 signal to signaling position.

2. In a classification signal for locomotives, a casing having open ends and an open top secured to one side of the locomotive, two oppositely disposed arms pivoted in the casing adjacent to one end thereof and near the top of the casing, each of said arms being twisted upon itself adjacent to the inner end thereof and said inner end offset and provided with a slot, 100 each of said arms having attached to the outer end thereof a signal which is of sufficient weight to normally swing the arm to retain the signal in the casing, rods guided through bearings in the casing and passing 105 through openings in the front wall of the cab of the locomotive, said rods having their outer ends provided with lateral extensions forming heads the inner edges of which being V-shaped and the said ends contacting 110 with the angle ends of the arms, the opposite ends of the rods being enlarged to provide heads designed to contact with the wall of the cab to limit the outward movement of the said rods, the heads of the respective rods 115 having imprinted thereon the color of the signal to which they are connected, means for locking the rods when the signals are brought to signaling position.

In testimony whereof, I affix my signature. 125
ROBERT FRANCIS STEWART.
